UNITED STATES PATENT OFFICE.

THOMAS B. EHART, OF PITTSBURG, KANSAS.

EXTENSION-TABLE.

1,217,727.

Specification of Letters Patent. Patented Feb. 27, 1917.

Application filed May 23, 1916. Serial No. 99,378.

To all whom it may concern:

Be it known that I, THOMAS B. EHART, a citizen of the United States, residing at Pittsburgh, in the county of Crawford and 5 State of Kansas, have invented new and useful Improvements in Extension-Tables, of which the following is a specification.

This invention relates to improvements in extension tables and has particular application 10 to a knock-down extension table.

In carrying out the present invention, it is my purpose to provide an extension table which may be readily and quickly extended to any desired length and wherein the component 15 parts of the table may be conveniently detached when it is desired to transport or store the table.

It is also my purpose to provide an extension table which will embrace the desired 20 features of simplicity, efficiency and durability, which may be manufactured and marketed at comparatively small cost and which may be quickly and conveniently extended and reduced in length.

25 With the above and other objects in view, the invention consists in the construction, combination and arrangement of parts hereinafter set forth in and falling within the scope of the claims.

30 In the accompanying drawings:

Figure 1 is a view in side elevation of an extension table constructed in accordance with my present invention, the same being shown reduced.

35 Fig. 2 is a top plan view of the table, the parts being shown extended and the top of the table removed.

Fig. 3 is a longitudinal sectional view through the table.

40 Fig. 4 is a collective view showing the extensible portions of the table in perspective.

Fig. 5 is a cross sectional view on the line 5—5 of Fig. 2.

45 Fig. 6 is a fragmentary end view of a modification.

Referring now to the drawings in detail, 1 designates a base constructed of any suitable material and preferably mounted upon 50 casters 2 so that the same may be readily moved about from place to place. Secured to the base 1 and upstanding therefrom is a pedestal 3. Mounted upon the upper end of the pedestal 3 is a supporting bar 4 formed 55 centrally with an opening alining with openings in the upper and lower ends respectively of the pedestal and passed through

these alining openings is a securing rod 5 having the lower end formed with a head 6 and the upper end screw-threaded as at 7 60 and threaded onto the end 7 of the rod 5 is a hand nut 8 whereby the bar 4 may be rigidly secured to the pedestal. Disposed upon the ends respectively of the bar 4 are transverse bars 9, 9 spaced apart in parallelism 65 and having the central portions thereof secured to the bar 4, while spanning the spaces between the ends of the bars 9 and secured to the extremities of such bars are guides 10, 10 lying parallel with each other and with 70 the bar 4 and disposed at the opposite sides of the bar 4.

In the present instance, each guide 10 comprises a base strip 11 and longitudinal guide strips 12, 12 secured to the upper surface of the base strip 11 adjacent to the respective side edges thereof and projecting upwardly therefrom. These guide strips 12, 12 are spaced apart in parallelism and formed in the confronting faces thereof are 80 longitudinally extending guide grooves 13. Slidably mounted within the guides 10, 10 respectively are slide bars 14 having the inner edges thereof in edge to edge contact with the adjacent sides of the inner bars 12 85 of the respective guides and formed on such edges of the slide bars 14 are longitudinally extending ribs 15 engaging in the adjacent grooves 13 respectively. Also slidably mounted within the respective guides 10, 10 90 are slide bars 16, 16 having the outer edges thereof in face to face contact with the inner surfaces of the outer bars 12 of the guides 10 respectively and formed on the outer edges of the bars 16 are longitudinally extending ribs 17 that engage in the grooves 13 in the inner surfaces of the outer bars 12. The inner edges of the slide bars 16 are in 95 face to face contact with the outer edges of the bars 14 and the guides 10, 10 and bars 100 14 and 16 coöperate to form, in effect, longitudinal side bars for the table. The bars 14 are capable of sliding movement outwardly from one end of the guides, while the bars 16 are adapted to move outwardly from the 105 opposite ends of the guides so that the length of the side bars formed by such guides and bars 14 and 16, may be increased. Secured to the outer extremities of the slide bars 14 is an end bar 18, while fastened to 110 the outer extremities of the slide bars 16 is an end bar 19. 20, 20 designate guide bars superimposed upon the slide bars 14, 14 respectively and having the outer ends thereof

seated within recesses formed in the upper surface of the end bar 18 and secured within such recesses. Each guide bar 20 is of a length less than the similar dimension of 5 the adjacent slide bar and the inner ends of the guide bars terminate short of the similar extremities of the slide bars, while the confronting edges of the guide bars are formed with stepped rabbets 21. Superim- 10 posed upon the slide bars 16 are guide bars 23 having the outer ends thereof seated within recesses formed in the upper edge of the end bar 19 and secured within such recesses, and the inner ends terminate short of 15 the inner extremities of the slide bars. The outer edges of the guide bars 23 are formed with stepped rabbets 24 adapted to fit into the rabbets 21 in the bars 20 respectively when the end bars are at their limit of in- 20 ward movement. The end portion of each bar 20, 23 adjacent to the particular end bar is of a width equal to the similar dimension of the space between the bars 12 and the particular guide 10 and the side edges of 25 such portions of the guide bars engage the confronting surfaces of the respective bars 12 of the particular guide, thereby holding the slide bars against rattling within the guides and reinforcing the side bars. The 30 upper surface of each slide bar 14, 16, adjacent to the inner end thereof, is equipped with a roller 25 adapted to bear against the under surface of the adjacent guide bar so as to eliminate friction between the parts.

35 Detachably connected to the upper surface of the frame thus formed are top forming sections 26, 26 placed end to end and having the meeting edges thereof adapted to engage each other when the adjustable side 40 bars of the frame are reduced in length. When, however, the slide bars are extended to increase the lengths of the side bars of the table, the meeting ends of the sections 26 of the table top separate and table leaves 45 are interposed between the confronting ends of the sections 26 so that the top of the table may be increased in length.

When the sections of the table are brought together, owing to the inward 50 movement of the slide bars 14 and 16, the table top is substantially square in top plan and if desired, segmental sections 27 may be secured to the side and end bars respectively of the table contiguous to the sections 55 26 so as to form a table top that is circular in top plan.

While I have herein shown and described one preferred form of my invention by way of illustration, I wish it to be understood 60 that I do not limit or confine myself to the precise details of construction herein described and delineated, as modifications and variation may be made within the scope of

the claims without departing from the spirit of the invention.

65

I claim:

1. An extension table comprising a pedestal, pairs of guide bars mounted upon said pedestal and spaced apart in parallelism, the bars of each pair having the confronting faces thereof formed with alining grooves, slide bars mounted between said pairs of guide bars respectively and ribs formed on the confronting faces of said slide bars and engaging in the adjacent 70 grooves, a second set of slide bars mounted between said guide bars respectively and having the inner edges in edge to edge contact with the outer edges of the first-mentioned slide bars, ribs formed on the outer 75 surfaces of said last-mentioned slide bars respectively and engaging in the adjacent grooves, end bars carried by the outer extremities of the first and second-named slide bars respectively whereby said slide bars may be moved outwardly of said guides in relatively opposite directions, top forming 80 sections connected to said first and second-named slide bars respectively and movable therewith to increase the length of the table top, and guide bars superimposed upon said slide bars respectively and connected to said end bars and movable with said slide bars into and out of the spaces between said first mentioned guide bars, the 85 confronting edges of companion guide bars being formed with interfitting rabbets.

2. An extension table comprising a pedestal, pairs of guide bars mounted upon said pedestal and spaced apart in parallelism, slide bars mounted between said pairs of guide bars respectively, a second set of slide bars mounted between the said guide bars, respectively, and having the inner edges in edge to edge contact with the outer edges of the first mentioned slide bars, end bars carried by the outer extremities of the first and second named slide bars, respectively, whereby said slide bars may be moved outwardly of said guides in relatively opposite directions, top forming sections connected to said first and second named slide bars respectively, and movable therewith to increase the length of the table top, and guide bars superimposed upon said slide 105 bars respectively, and connected to said end bars and movable with said slide bars into and out of the spaces between said first mentioned guide bars.

In testimony whereof I affix my signature 120 in presence of two witnesses.

THOMAS B. EHART.
